UNITED STATES PATENT OFFICE

EZRA E. CLARK, OF NEWTONVILLE, MASSACHUSETTS; FRANCES CLARK EXECUTRIX OF
SAID EZRA E. CLARK, DECEASED

VALVE FOR SPRINKLER SYSTEMS

Application filed June 8, 1928. Serial No. 283,969.

This invention relates to valves such as are used in sprinkler systems for controlling the flow of water from the supply to the system. Under normal conditions a valve for this purpose is held closed by the pressure in the system but is constructed so that when the pressure in the system decreases, as for instance would be the case if a sprinkler head opened, the valve will automatically open to allow water to flow from the supply into the system.

When the valve opens due to the opening of a sprinkler head it is desirable not only that the valve should in opening be moved out of the waterway so as to allow a free flow of water to the system, but is also desirable that some means be provided to lock the valve in its open position so as to guard against any closing tendency of the valve while the water is flowing therethrough in either direction.

My present invention relates to the means for locking the valve open and it has for its object to provide a novel construction by which when the valve is fully opened it will automatically lock itself in such open position. This is accomplished herein by providing means for guiding the valve in its opening movement, which means permits the valve to have a gravitational movement after it is fully opened and by further providing means co-operating with the valve after it has had its gravitational movement to lock the valve positively in open position.

In order to give an understanding of the invention I have illustrated in the drawing one embodiment thereof which will now be described after which the novel features will be pointed out in the appended claims.

The figure is a vertical sectional view of a valve embodying my invention, said figure showing the valve open in full line position and closed in dotted line position.

In the device shown in the figure, 1 indicates a valve casing having an inlet 2 communicating with the source of water supply and terminating in a valve seat 3 and also having a discharge or outlet 54 leading to the system. The water valve controlling the supply of water through the inlet is indicated at 4 and it is adapted to seat on the valve seat

3 as shown by dotted lines in the figure. This valve is pivotally mounted to swing from closed to open position, said valve being carried by an arm 5 which is pivotally mounted at 6 to the end of a link 7 which in turn is pivoted to the valve casing at 8.

When the valve is in closed relation the link 7 has the dotted line position in the figure, the pivotal connection 6 between the link and the arm 5 being in a position to permit the valve to seat properly on the seat 3. At this time the link lies close to a stop pin 9 which limits the upward swinging movement of the link.

The valve shown in the figure is of the differential type, it being provided with an annular flap portion 11 of flexible material which is considerably larger than the valve seat 3 and is adapted to seat on another valve seat 12 which encircles the valve seat 3. The valve is also constructed with a chamber 13 between the valve seats, which chamber normally has communication with the atmosphere when the valve is closed.

Owing to the fact that the valve flap 11 is of larger area than the opening through the valve seat 3 a pressure in the system less than that of the supply pressure will suffice to hold the valve closed but if the pressure in the system falls below a predetermined point, as would be the case if a sprinkler opened then the reduced pressure on the upper side of the valve will be insufficient to hold the valve closed and the latter will open thus allowing water to flow to the system. As the valve opens it swings about the pivot 6 as an axis and during the first opening movement this pivot is located at the dotted line position in the figure.

The construction and mounting of the link 7 is such that when the valve is pretty well opened said valve is permitted to have a downward gravitational movement, and means are provided co-operating with the valve when it has completed its gravitational movement to lock the valve in open position.

It will be noted that the valve casing 1 is provided with a recess or space 14 below the link 7, the link 7 being situated above the

bottom of the recess 14 when the valve is closed.

The relation between the link 7, the arm 5, and the recess 14 is such that the wall 15 of the recess is situated beyond the end of the link 7. When, during the opening of the valve, it approaches its open position, it, together with the link 7, will gravitate downwardly, the link 7 swinging from the dotted 10 to the full line position and resting against the bottom of the recess 14 while the end of the arm 5 drops behind the wall 15 of the recess as shown by full lines in the figure. When the valve is in this position it is positively 15 locked against closing movement because the pivot 6 has been carried below the wall 15 of the recess and the face 16 of the arm is resting against said wall. The valve is thus fulcrumed on the wall of the recess at the point 20 16 and any closing movement of the valve will be resisted by the arm or link 7. In order to close the valve it is necessary to raise it so as to swing the link into the dotted line position wherein the pivot 6 is above the top 25 of the recess 14.

With this construction, therefore, the valve will swing into open position and the guiding means for controlling the swinging movement of the valve are such that when the 30 valve is opened it is permitted to have a gravitational movement into a position where it becomes positively locked against closing movement.

The arm 5 is so designed that when the 35 valve is closed the face 16 thereof rests on the upper edge 17 of the wall of the recess.

In all this embodiment of the invention, therefore, the guiding means for the valve is such as to permit the valve to swing into its 40 open position and is also such that when the valve is in open position it may have a gravitational movement (herein illustrated as at substantially right angles to the opening movement of the valve) into a new position 45 in which it is automatically locked from closing.

While I have illustrated herein one selected embodiment of my invention I do not wish to be limited to the constructional features 50 shown.

I claim:

1. In a valve structure for sprinkler systems, the combination with a valve casing having a valve seat, of a valve therefor, a 55 movable member to which the valve is pivotally connected for swinging movement toward and from the valve seat, said member and valve being arranged to have a gravitational movement after the valve is opened, 60 and means co-operating with said valve and member when in the position to which they gravitate to lock the valve against closing movement.

2. In a valve structure for sprinkler systems, the combination with a valve casing 65

having a valve seat, of a valve therefor, a swinging member pivoted to the casing and to which the valve is pivoted, said member and valve being capable of having a gravitational movement after the valve has opened, and means co-operating with said valve and member in the position to which they gravitate to lock the valve against closing movement. 70

3. In a valve structure for sprinkler systems, the combination with a valve casing having a valve seat, of a valve adapted to seat on the valve seat, a swinging member pivoted to the casing and to which the valve is pivoted, said valve casing having a recess beneath the member, and said member and the adjacent end of the valve being capable of gravitating into said recess after the valve has opened, whereby the valve is locked in open position. 75

4. In a valve structure for sprinkler systems, the combination with a valve casing having a valve seat, of a valve therefor, a link member pivoted to the valve casing and to which the valve is pivoted, said casing having a recess into which said link and the adjacent end of the valve gravitates after the latter has opened, said valve being locked in its open position by engagement with the wall of the recess. 80

5. In a valve structure for sprinkler systems, the combination with a valve casing having a valve seat, of a valve therefor, a movable member to which the valve is pivotally connected for swinging movement toward and from the valve seat, said member and valve being arranged to have a gravitational movement in the opening movement of said valve, and means co-operating with said valve and member when in the position to which they gravitate to lock the valve against closing movement. 90

6. In a valve structure for sprinkler systems, the combination with a valve casing having a valve seat, of a valve adapted to seat on the valve seat, a swinging member pivoted to the casing and to which the valve is pivoted, said valve casing having a recess beneath the member, and said member and the adjacent end of the valve being capable of gravitating into said recess in the opening movement of said valve whereby the valve is locked in open position. 100

In testimony whereof, I have signed my name to this specification. 105

EZRA E. CLARK.
